UNITED STATES PATENT OFFICE.

JOHN J. WALSH, OF YONKERS, NEW YORK.

CABLE-HANGER.

1,080,130.

Specification of Letters Patent.

Patented Dec. 2, 1913.

Application filed November 21, 1912. Serial No. 732,666.

To all whom it may concern:

Be it known that I, JOHN J. WALSH, a citizen of the United States, residing at Yonkers, county of Westchester, and State 5 of New York, have invented certain new and useful Improvements in Cable-Hangers, of which the following is a full, clear, and exact description.

This invention relates to cable hangers or 10 clips for suspending a telephone, telegraph and like cable from a messenger wire or cable, and its chief object is to provide a hanger or clip which can be applied to the messenger wire or cable without the use of 15 a tool of any sort and which when applied will not only hold the suspended cable in place with complete security but will also be incapable of creeping or sliding along the messenger wire.

20 To this and other ends the invention consists in the novel features of construction and combinations of elements hereinafter described, and more particularly pointed out in the appended claims.

25 One form of the invention is illustrated in the accompanying drawing, in which—

Figure 1 shows my improved hanger or 30 clip in perspective, with its parts separated. Fig. 2 is a side view showing the hanger or clip applied to the messenger wire but with the cable-suspending ring open. Fig. 3 is a similar view, but showing the suspending ring closed. Fig. 4 is a cross section, on a larger scale than that of Fig. 1, of the saddle which is seated on the messenger wire. Fig. 5 is a section on line 5—5 of Fig. 1, but on a larger scale.

In the form illustrated, my improved 35 cable hanger comprises a saddle portion 10 and a ring portion 11, the two parts being separable as indicated in Fig. 1. The saddle portion is made of a rectangular piece of heavy sheet metal bent to the proper shape, having depending sides 12, 13, and laterally 40 extending wings 14, 15. The sides are provided with apertures in the form of longitudinal slots 16, 17, at about the points where the rings and sides are joined. One of the slots, as 16, is wider than the other, as shown 45 in Fig. 1.

The hanger 11 is a divided or split ring 50 with hooked ends made of a strip of sheet metal bent to ring shape, having an end 19 bent up at practically a right angle and 55 the other end 20 bent at a sharper angle.

To increase the stiffness of the ring and yet leave it with suitable flexibility it may have a transverse bend, producing the cross section shown in Fig. 5.

In using the hanger the saddle portion 60 10 is first seated on the messenger wire 21 (shown in the drawing as a seven-strand wire rope or cable) after which the hooked end 19 of the ring 11 is passed through both slots 17, 16, thus putting the parts in the 65 position shown in Fig. 2. The ring is now compressed to bring the hooked end 20 into engagement with the slot 16, as in Fig. 3. This locks the ring to the saddle, since the 70 ring is under tension tending to force the hook 20 into the slot instead of out of it. Where it is desired to hang the cable by 75 putting a number of hangers on the messenger wire and then drawing the cable through the hangers in succession it is important that the hangers grip the wire 80 tightly enough to prevent sliding thereon as otherwise they would bunch together when the cable is drawn through. To accomplish the desired result with my hanger in the 85 form illustrated, the saddle 10 is provided with one or more lugs, as 22, stamped down from the top of the saddle. This lug seats into the angular space between the uppermost strands of the messenger wire 21. Since 90 the hanger ring abuts against the bottom of the twisted messenger cable it is evident that by reason of the lug the hanger cannot move along the messenger cable unless either the latter rotates or the hanger itself revolves about the axis of the messenger cable. 95 As neither of these contingencies can happen in practice it is seen that the lug effectually prevents movement, or at most permits only a limited movement, of the hanger along the messenger cable.

In putting up hangers with a tool, as is the usual practice, to bend or crimp a part or parts of the hanger, it frequently happens 100 that the rather sharp bending to which a part of the device is necessarily subjected causes the galvanizing to crack, chip off, or otherwise be damaged, with the result that the iron or steel hanger rapidly deteriorates by reason of the inevitable rust or corrosion. 105 With my hanger, however, there is no such bending of any part as would result in injury to the galvanizing, and consequently the life of the hanger is markedly lengthened.

It is to be understood that the invention is not limited to the specific device illustrated but can be embodied in other forms without departure from its proper spirit and scope as defined by the following claims.

I claim:

1. A cable hanger comprising, in combination, a saddle adapted to be seated on a messenger wire and having depending apertured sides, and a ring having a hooked end passing through the apertures in both said sides underneath the messenger wire, and another hooked end adapted to lock into the aperture in one of said sides.
15. 2. A cable hanger comprising, in combination, a saddle adapted to be seated on a messenger wire and having depending apertured sides and provided with means to engage the messenger wire and oppose sliding on said wire, and a ring having a hooked end adapted to pass through the apertures in both sides underneath the messenger wire.
25. 3. A cable hanger comprising in combination, a saddle adapted to be seated on a messenger wire and having depending apertured sides, and a split ring having a hooked end adapted to pass through both apertures underneath the messenger wire and a hooked end adapted to engage an aperture underneath the other hooked end.
30. 4. A cable hanger comprising in combination, a saddle adapted to be seated on a messenger wire and having depending apertured sides provided with laterally extending wings; and a split ring, having a hooked end adapted to pass above one of the wings and through both apertures underneath the messenger wire, and a hooked end adapted to

engage an aperture underneath the other hooked end.

5. A cable hanger comprising, in combination, a sheet-metal saddle of elongated form adapted to be seated on a messenger wire and having depending sides provided with longitudinal slots; and a split ring of sheet metal having hooked ends, one adapted to pass through both slots underneath the messenger wire, and the other adapted to engage a slot under the first hooked end.

10. 6. A cable hanger comprising, in combination, a saddle adapted to be seated on a messenger wire, having depending apertured sides and provided with means to oppose sliding on the messenger wire, and a split ring having hooked ends, one adapted to pass through both apertures in the sides of the saddle and to underlie the messenger wire, and the other adapted to engage an aperture under the first hooked end.

15. 7. In a cable hanger, a sheet-metal saddle adapted to be seated on a messenger wire and having depending apertured sides, and provided with a lug to engage the messenger wire to oppose slipping thereon.

20. 8. In a cable hanger, a saddle shaped to be seated on a messenger wire and having depending apertured sides to receive a cable-supporting ring, and having a lug depending from the top to engage the messenger wire to oppose slipping thereon.

25. In testimony whereof I affix my signature in the presence of two subscribing witnesses.

JOHN J. WALSH.
